UNITED STATES PATENT OFFICE

JACQUES SCHLUMPF, OF HORCHEIM, NEAR COBLENZ, GERMANY

DEVICE FOR SUBDIVIDING LIQUID CONTAINERS

Application filed May 31, 1929, Serial No. 367,217, and in Germany May 29, 1928.

In the use of certain liquid containers, particularly those which are employed for the reception of dye liquids in yarn dyeing apparatus, the need arises for sub-dividing them into different compartments either for the purpose of rendering only a part of each container available for use or for charging the individual compartments thereof with different liquids.

In order to provide such dividing partitions it has been proposed to arrange projecting guides parallel to one another on the inner walls of the container so that a smooth plane partition wall can be slidden into their edges after the manner of a slide. The packing of the wall was attained by providing packing materials in the rim or on the edge of the intermediate wall. These projecting retaining guides for the partition wall proved however to be unsuitable in use, and particularly to be a source of more or less trouble when it was desired to clean the container. Further, the need frequently arose of making the compartments of the container of different sizes.

In order to remove these disadvantages and to take into account the before mentioned requirements, each partition serving for dividing the container into several compartments is provided according to the invention on its lower and lateral edges with a tubular deformable or flexible member which can be placed under such tension by being connected to a suitable source of pressure, that it is forced tightly against the adjacent side and base surfaces of the container in order to support the partition against the lateral liquid pressure of a filled compartment, and to obviate the need for supporting guides or ledges mounted on the wall of the container.

By suitably constructing the devices employed for transmitting the vertical pressure on the base of the container to the wall thereof, it is readily possible to mount the partition in any desired position in the container without employing any special attachment devices and to vary the size of the compartments as required.

In the accompanying drawings:—

Figure 1 is a vertical transverse sectional view.

Figure 2 is a section on the line V—V of Figure 1.

A container 1 suitable for the application of the invention has the upwardly converging side walls 2 and a plane base 3. The partition wall 4 serving for sub-dividing the interior of the container is mainly a plane plate-like member, the lateral and lower bounding edges of which correspond to the transverse contour of the bath or container 1, and are constructed so as to leave a free intermediate space giving sufficient freedom of movement for the intermediate wall.

The lateral and lower edges of the wall 4 are formed with the longitudinal grooves 5 which, for example, are of semi-circular cross section. A tubular packing member 6 consisting of rubber or other deformable material reinforced, for example, by fabric tapes is seated in the groove 5, and its diameter is such that it fills out or bridges over the intermediate space existing between the lateral and bottom edges of the dividing wall on the one hand and the inner surfaces of the side and bottom walls of the container on the other hand.

The two ends of the packing tube are passed through appropriate apertures in the transverse clips 7 pivotally secured to the upper edge of the partition wall 4, for engaging over the rolled edge 14 of the container and for taking up the lateral reaction of the packing pressure. One end of the tube or pipe is tightly closed by a stopper 8, whilst the other end is provided with an inflation valve 9 for connecting the interior of the packing tube to a source of pressure such as an air pump or the like. By means of these clips 7 the partition wall is held in proper position within the container 1 against longitudinal movement while inflating the tube. Under the action of the liquid or gaseous pressure medium introduced at an appropriate pressure into the pipe 6, the latter is forced against the contacting parts of the walls of the container and the rim of the partition wall so as to form a liquid tight joint.

It will thus be seen that, when the pressure

is injected into the tube, such tube will expand between and fill the space in the container, of the partition wall and the side walls and bottom of the tank. The fact that the side walls of the container converge upwardly, and that the space between the ends of the partition and sides of the container are filled by the inflated tube, any tendency of the partition to rise will be effectively prevented, and such partition firmly held in its position so that a liquid-tight joint is provided, which will prevent any leakage of liquid from one compartment, into an adjacent compartment. Furthermore, the operator is assured of the proper positioning of the partition, while inflating the tube, thus obviating the necessity of holding such partition by hand.

I claim:—

- 20 1. Means for subdividing a liquid container having upwardly convergent side walls, comprising a removable partition wall adapted to be positioned at any point longitudinally within the container, an inflatable packing element between the end and bottom edges of the partition wall and the side and bottom walls of the container, and means carried by the partition wall and releasably engaged with said side walls of the container 30 for holding said partition wall during the inflation of said packing.
- 25 2. Means for subdividing a liquid container having upwardly convergent side walls, comprising a removable partition wall having end and bottom edges in parallelism with the side and bottom walls of the container, a hollow deformable packing element supported in the space between said partition edges and the said walls of the container, and 35 means on said packing element for connection with a source of pressure for expanding the packing to produce a liquid-tight joint between the partition wall and container.
- 30 3. Means for subdividing a liquid container having upwardly convergent side walls, comprising a removable vertical partition wall having end and bottom edges conforming with said side and bottom walls of the container, and in spaced parallelism therewith, said partition wall edges being longitudinally grooved, an inflatable packing element seated in said grooved edges of the partition wall, and pivoted clips carried by the partition wall for engagement with the mouth of the container whereby to hold said partition wall in position during the inflation of said packing.

In testimony whereof I affix my signature.
JACQUES SCHLUMPF.
